INVENTOR

Frank M. Ashley

ATTORNEY

UNITED STATES PATENT OFFICE.

FRANK M. ASHLEY, OF BROOKLYN, NEW YORK.

FOUNTAIN PEN.

Application filed February 17, 1928. Serial No. 254,955.

My invention relates to pens.

The object of my invention is to provide a dip pen or a fountain pen with a feed plug having a bore for holding an ink-stick 5 into which an ink-stick may be inserted from the exposed front end without disassociating any of the parts of the pen.

A further object is to provide a fountain pen that may be filled and used with ordinary ink, and that also may be provided with a stick of indelible ink and filled with water, which when coming in contact with the ink-stick, will dissolve a portion thereof to provide a writing fluid.

15 A further object is to provide a pen of the self filling type having a feed plug adapted to hold an ink-stick that may be inserted in the front end of the plug and pushed therethru or therein to be acted upon 20 by water to provide a writing fluid for the pen, without disassociating any of the parts of the pen construction.

Referring to the drawings which form a part of the specification,

25 Fig. 1 is a longitudinal, partly sectional view of a fountain pen embodying my invention.

Fig. 2 is a longitudinal sectional view of the pen section and feed-plug illustrating a 30 modified form of construction less expensive in cost of construction.

Fig. 3 is a longitudinal sectional view showing a further feature of construction especially adapted for use with dip pens.

35 Fig. 4 is a cross sectional view taken on line 4—4 of Figure 1, shown on an enlarged scale.

Fig. 5 is a cross sectional view taken on line 5—5 of Figure 1.

40 Fig. 6 is a longitudinal plan view of the feed-plug with a portion broken away to disclose the relative size of the ink-duct, pockets and cross bores.

Fig. 7 is a longitudinal sectional view 45 taken on line 7—7 of Figure 6, and further illustrating said pockets.

'Figs. 8 and 9, are longitudinal sectional views showing the cheapest forms of construction for use with self-filling fountain 50 pens using the ink-stick, but are not adapted for use with dip pens.

In patents heretofore granted to me for improvements in pens using an ink-stick, it has been necessary to disassociate the parts

in order to insert the ink-stick, and this defect has made the pens unmarketable, as the fingers are sure to become ink-stained when the parts are being taken apart to fill or provide a new ink-stick.

Also, the diameter of the ink-sticks heretofore used have been too large, preventing the use of a capillary bore which would prevent ink from flowing from the pen thru the bore if no plug or ink-stick were located therein, and the bore was open at the front 65 end of the feed-plug.

The small diameter of ink-stick, commonly called indelible leads, and used in pencils, is small enough to be held in a bore that will not permit the ink to flow therefrom at its 70 front end, and therefore I am able to provide a pen that may be used with or without the ink-stick, and to fill the pen reservoir without disassociating the parts.

In the prior patents above referred to it 75 was necessary to remove the pen section from the body or barrel of the pen in order to insert the ink-stick in the back end of the feed-plug, and therefore a sack type of reservoir self filling pen could not be 80 used for the reason that the sacks are cemented directly to the back end of the pen sections; therefore it was necessary to use a dropper to fill the reservoir.

The present invention permits the use of 85 an ink-stick with any type of self-filling sack pen.

Furthermore, the pen feed-plug may be made in various sizes to fit any of the standard make of pens, and sold as a separate article of manufacture for use by persons who have purchased pens of such standard construction.

A, indicates the barrel of a fountain in which a sack B, is held in the usual manner, and filled in the usual way.

C, indicates the pen section which is attached to the barrel A, by a screw C', or may be made with a sliding frictional joint in a manner well known to this art.

The pen section C, is provided with the usual bore C², in which the feed-plug D, is held by friction in the usual manner. The feed-plug D, is provided with the usual feed-duct E, which extends from near the front end to the back end of the plug as illustrated in Figures 1, 8 and 9, as is usual, or may extend entirely thru the front end as

illustrated in Figure 3, at E', when the pen is to be used as a dip pen, as it permits the ink to flow directly from the inkwell into the feed duct at E' when the pen is dipped 5 into said inkwell.

D' indicates the lower side of the feed plug.

F, indicates a bore of small diameter which I prefer to have extend the entire 10 length of the feed plug in open communication with the reservoir, and just large enough in diameter to permit an ink-stick 15 of small diameter, such as used in "Ever-sharp" pencils and which are about forty-five one thousandths of an inch in diameter. I may, however, use a smaller diameter if desirable, or I may use a larger diameter, such as heretofore used, and when using ordinary ink, insert a rod of hard rubber in the bore 20 to prevent ink from flowing from the bore by reason of the capillary action not being sufficient to hold the ink therein, as will be readily understood.

The smaller diameter of bore is such that 25 it acts as a capillary tube when the ink-stick G, is removed therefrom, and no ink will flow from its outer end when the pen is being used with ordinary ink, and it also serves as a filling channel in filling the reservoir rapidly with ink.

The feed-plug may be provided with one or more holes H, which extend thru the partition I, to connect the feed-duct E, and bore F, in open communication, as illustrated in Figures 2-3-6-7 and 8. In Figures 1-4-6 and 7, I have shown the passages H, as larger in diameter than the width of the feed-duct E, to provide pockets to hold a larger quantity of water in contact with the 30 ink-stick than the smaller holes would hold, which serves to provide the writing fluid or a more uniform color, especially when using the pen as a dip pen, that is, inserting the pen point into water to provide a writing fluid, as the fresh water mixes with some of the dissolved fluid from the ink-stick still remaining in the pockets. The capillary holes H'-H' respectively, formed in the lower 35 part of the plug, are made as small, or smaller than the diameter of the bore F, and permit the feed-plug to be more easily cleaned and the sediment removed which collects from the ink-stick as it dissolves, which sediment usually consists of starch grains used 40 to hold the color of the stick.

In Figure 8, I have shown the bore F² enlarged in diameter relative to the size of the bore at its forward end, and have shown the holes H located nearer the inner end of the 45 plug.

This construction permits a larger drill to be used in drilling the bore for this part of its length, which is an advantage in making the plugs as the small drills break very 50 easily in making a long bore, and this con-

struction also permits a supply of water from the reservoir to flow around the ink-stick and quickly provide a writing fluid.

In Figure 9, I have shown the most simple form of my invention, the ink-stick being 70 pressed entirely thru the bore as illustrated, or only part way therethru, and the water from the reservoir acting on the rear end of the stick only, the color being carried into the reservoir to provide the writing fluid therein.

It will be understood that the writing fluid provided by the use of the ink-stick is not a true record ink, since it contains no nut-galls or iron, but it serves as a convenient 80 writing fluid for most purposes.

In use, the parts are assembled as illustrated in Figure 1, and after removing the cap J, the ink-stick G, is inserted into the bore F, as illustrated and the reservoir then 85 filled with clean water which will come in contact with the ink-stick and dissolve a portion thereof to provide a writing fluid, as will be readily understood.

If ordinary ink is to be used, simply fill 90 the reservoir with the ink in the usual way, unless a bore of large size is formed in the ink-plug, in which event the hard rubber rod having the same diameter and length as the ink-stick, should be inserted in the bore 95 before the pen is filled with ink.

Having thus described my invention I claim as new:

1. A feed plug for a pen having a feed duct and a bore open at its front end and extending entirely therethru and adapted to receive and frictionally engage an ink-stick.

2. A feed plug for a pen having a feed duct and a capillary bore open at its front 105 end and adapted to receive and hold an ink-stick.

3. A feed plug having a feed duct and a capillary bore extending parallel therewith and open at its front end to the atmosphere 110 and having holes leading from said feed duct to said bore.

4. A feed plug having a feed duct and a capillary bore extending parallel therewith having a diameter of 46/1000 of an inch, 115 said bore being open at its front end to receive an ink-stick.

5. As stated in claim 4, and having holes leading from said duct to said bore.

6. A feed plug having a feed duct and a capillary bore extending parallel thereto having its front end exposed to the atmosphere and having holes leading from said duct across said bore to the lower side of the plug.

7. As stated in claim 6, and the diameter of said holes being enlarged relative to the width of said duct between said duct and bore to form pockets as set forth.

8. A fountain pen comprising a reservoir 130

and pen section, a feed plug held in said pen section having a feed-duct and a capillary longitudinally extending bore in open communication therewith, and an ink-stick 5 in said bore.

9. A fountain pen comprising a reservoir and pen section, a feed plug held in said pen section having a feed-duct and a capillary longitudinally extending bore extending en-

tirely therethru adapted to hold an ink-stick. 10
10. As stated in claim 9; and an ink-stick in said bore.

11. As stated in claim 9; and a rod of hard material for closing said bore.

In testimony whereof I have affixed my 15
signature.

FRANK M. ASHLEY.
